BED CONSTRUCTION

Ernest J. Sweetland, Piedmont, Calif.

Application July 9, 1946, Serial No. 682,395

11 Claims. (Cl. 5—63)

1

This invention relates to a bed of special construction and particularly to a bed for use in hospitals and such other places as may require a bed capable of being raised and lowered to promote the comfort, convenience and safety of the occupant, and to facilitate the work of nurses in attendance.

As is well known, hospital beds are built much higher than ordinary home beds so that nurses in attendance may care for the patient who occupies the bed without the tiresome bending and stooping that would be necessary in a bed built to the height of ordinary home beds. While hospital beds, which are usually from 32 to 36" in height to the top of the mattress, are a great convenience to the nurses in attendance, they are not only inconvenient, but, in some cases, are actually dangerous from the standpoint of the patient, since patients frequently fall from these high beds and are seriously injured.

Furthermore, many hospital patients are disturbed by the unusual height of the beds and would be much more comfortable in a bed of ordinary height.

Aside from the practical aspects of the matter, there is a distinct aesthetic value in a hospital bed which can be lowered to ordinary bed height, and thus provide the hospital room with a much more comfortable and homelike atmosphere.

One of the objects of my invention is to provide a bed which may be lowered at night to minimize the danger of serious injury which may be caused if the patient falls out of bed.

Another object is to provide a bed for the use of invalids which is maintained at hospital-bed height during the hours when the occupant requires the attendance of a nurse, and which can conveniently be lowered to the height of an ordinary home bed at other times.

A further object of my invention is to provide a bed with power means of elevating and lowering the bed, which means is concealed beneath the springs of the bed in such manner that moving parts are hidden from view and are so protected that bed clothing and other objects cannot become entangled in the moving parts.

Another object of my invention is to provide a bed with a combination of cam and toggle means for raising and lowering the upper structure of said bed, so arranged that maximum power is applied to said toggles when the angle between the toggle members requires the maximum application of force, the cam arrangement being such that the power diminishes and the

2

speed of toggle movement increases as the toggle members gradually straighten.

A further object of my invention is to provide switch means to govern the power unit in the bed in such a manner that the switch automatically cuts off the electric current and thereby stops the motion of the bed automatically when the movable portion of the bed reaches the limit of travel, either in the upward or downward direction. This makes it possible to use a small motor, and renders it unnecessary for the operator to stand by and to shut off the power when the limit of travel is reached.

A further object is to provide a bed of the class described with switch control means which automatically locks in the position to which the switch is thrown, and remains so locked until the moving parts of the bed have reached the limit of travel, at which point the lock is partially released automatically, but in such a manner that it permits the bed to move only in the opposite direction to that which it took in the last operation.

A further object is to provide an auxiliary switch which permits the bed to be stopped at any desired intermediate height.

The invention possesses other advantageous features, some of which with the foregoing will be set forth at length in the following description where one form of the invention has been selected for illustration in the drawings accompanying and forming a part of the present specification. In said drawings, one form of the invention is shown, but it is to be understood that it is not limited to such form, but only by the scope of the appended claims.

My invention will be understood by reference to the following description of the appended drawings, wherein Fig. 1 is a side elevation of the bed at full height.

Fig. 2 is a fragmentary view of a front elevation of the portion of a toggle joint.

Fig. 3 shows a fragmentary view of a side elevation of a portion of a pair of toggles to show the stop means which prevents the toggles from bending inwardly beyond a vertical line. In this view the bolts 21 and attendant parts, which are omitted from Fig. 2, are shown.

Fig. 4 is a side elevation of the bed lowered to its lowermost position.

Fig. 5 is a plan view of the bed with springs and mattress removed to expose the operating parts of the bed.

Fig. 6 is a plan view of the switch means used to control the raising and lowering of the bed.

Fig. 7 is a sectional elevation of Fig. 6 taken along the lines 7—7 of Fig. 6.

Fig. 8 is a side elevation of one of the switch latch elements in depressed position.

Fig. 9 is a plan view of Fig. 8.

Fig. 10 is a wiring diagram showing one manner of connecting the switch.

In all of the views the springs of the bed are eliminated, as are also the customary mechanisms for elevating portions of the springs and mattress. These appliances may be used in conjunction with my bed, but since they form no part of the present invention they have been omitted. In the drawings where fastening means, such as bolts, nuts, rivets, etc., are omitted, it is to be assumed that the parts are welded or brazed together.

Referring in detail to Figs. 1, 2, and 3, the numeral 1 indicates the mattress; 2 the head, and 3 the foot of the bed; 4 represents the frame which carries the springs (not shown) of the bed; 5 represents angle irons which form the structural side members of the bed, and support for the spring structure, and which are welded to cross members 5a to form a rectangular frame to tie the head 2 and foot 3 together. The usual conventional means (not shown) may be used in securing the head and foot to this frame.

The lower structure of the bed is supported upon a rectangular frame of structural steel comprising the longitudinal angles 6, which are tied together by the cross members 7. Casters 8 of usual form are mounted at the ends of the angles 6, and these are serviceable for moving the bed, whether it is in its upper or lower position, since the head and foot of the bed do not reach the floor when the bed is in its lowered position. The weight of the bed, when it is in its lowered position, is supported upon four vertical posts 9, which extend upwardly from the cross angles 7 and are engaged by the cross angles 11.

Each of the legs which support the bed comprises four links, each of which is united together to form an effective toggle, and due to their peculiar construction these toggles afford the maximum stability for the bed, whether it is in the upper, lower, or an intermediate position.

The upper links 12 are pivoted at the top by the pins 13 to vertical bearing plates 13a which are welded to the angles 11, and the lower toggle members 14 are similarly pivoted with pins 15 and are hinged together at the junction point between the members 12 and 14 by the pins 17. The toggles are spaced apart by spacing blocks 16, which are held in place by pins 17 and the nuts 18 (see Fig. 2). The spacing blocks are provided with the holes 19, which accommodate bolts 21 to form a convenient and adjustable attachment for the flexible cables 22 and 22a by means of yokes 23 and nuts 24. The cable ends are enlarged at the ends 44 to hold them in place. The upper toggle members 12 are provided with stops 26, which prevent the angles passing the center line when the bed is raised to its uppermost position.

The coil springs 29 perform the important function of urging the toggles to bend outwardly when the cables 22 and 22a are slackened to lower the bed. Without spring means to bias the toggles outwardly they would tend to rest on dead center when the bed is in its uppermost position and this would prevent the proper lowering of the bed when the cables were slackened.

Resting upon the shelf 32 is the motor 33 which is back geared to a very slow speed through worm gears encased in the housing 34. The slow speed shaft 35 of the motor is provided with pinion 36, which engages the gear 37, which in turn is keyed to the shaft 38. The shaft 38 is supported in bearings 39 carried by the plates 41, one of which is welded to each of the angles 5. Four cams, 42, 42a, 43 and 43a, are keyed to the shaft 38. These cams are provided with peripheral grooves to guide the cables 22 and 22a.

The general contour of the cams is best shown in Figs. 1 and 4, where it will be noted that when the bed is in its lowered position and ready to be raised, the shaft 38 will turn in clockwise direction (Fig. 4). At this lowermost point the leverage exerted by the cams is very great to provide the maximum power against the toggles when maximum force is required; that is, when the toggles lie with an included angle of about 60 degrees. As the shaft 38 continues to rotate and the toggles straighten the leverage of the cams diminishes as the load becomes lighter. The advantage of cams to perform this function rather than the use of simple cylindrical winding drums is obvious for the following reasons:

For the sake of economy in construction, it is desirable to use as small a motor as possible, and the cam and toggle principle make it possible to use a much smaller motor than would otherwise be required, because a small motor could not be used without a high degree of leverage when the included angle between the toggle members is most acute and the force required is greatest. Therefore, if simple cylindrical winding drums were used, the drums would of necessity have to be small and the time required to raise the bed would be very much longer. The cams tend to equalize the load on the motor and to speed up the operation. Another advantage of using cams is that they eliminate any problem of keeping the cables perfectly straight and in their desired operative position.

The plate 32 which supports the motor is secured in position by the posts 45, which are welded to the angles 46 and 47. The plate 32 is further braced by the struts 48 which are welded to the angle 49. A pair of plates 51 are welded to the under side of plate 32 to form a bearing for the lever 52. This lever performs the very important function of preventing excessive endwise movement of the upper structure of the bed with relation to the base portion when the bed is raised or lowered. Lever 52 is pivotally secured between the upright posts 53 by the pin 54, and is pivotally secured between the plates 51 by the pin 55. In the normal use of a bed the bed surface is unevenly loaded with the greater weight near the head end of the bed. This results in an uneven force on the cables 22 and 22a and this unevenness would produce prohibitive endwise movement of the upper structure were it not for the lever 52. The uprights 53 are under considerable strain when the bed is being raised or lowered so that they are reinforced by a pair of angle braces 56, which are welded to the posts 53 and angles 6 in the manner indicated in Fig. 5.

Up to this point it will be understood that the bed comprises an upper and lower structure pivotally supported upon four sets of toggles which serve as legs for the bed, and that the height of the bed is adjusted by power means which straightens the toggles to a perpendicular posi-

tion when the bed is at its maximum height, and which bend with a knee action when it is desired to lower the bed, and that the two main portions of the bed are linked together by the lever 52 which stabilizes the structure and prevents relative endwise movement between the two main parts of the bed. It will also be noted that each toggle is double in construction to provide maximum stability. When the bed is in its high position the cables are taut, and each toggle member 14 is provided with the stop 26 which abuts the flat surface of the toggles 14, so that the toggles are quite rigid when in their straightened position.

The upward and downward movement of the bed is effected by reversal of the motor. To control the motor in the simplest possible manner, I have devised a switch of unique construction which prevents any possibility of error on the part of inexperienced nurses or employees who may have occasion to use the bed.

The switch 61 is located in a housing which is supported upon the plate 62, which is held in place by means of the posts 63 which are welded to the angle 64 and the posts 65 which are welded to the angle 47. The control rod 67 enters the switch box, as shown in Figs. 1 and 7, and is supported by the angle plate 68, and terminates in the knob 69 by means of which it is operated.

The detailed construction of the switch will be understood by reference to Figs. 6 to 10, inclusive. Referring to these figures, numeral 61 designates the switch in general, comprised of the box 71a, a partition member 72a, and the cover 73, which cover, as well as a portion of the partition member 72a, are removed in Fig. 6 to better illustrate the working parts of the switch.

The switch comprises four cylindrical posts 14, which are made of insulating material, such as Bakelite. These are held firmly in place by countersunk screws 75. Inserted in the tops of each of these posts are three contact points 76. These are preferably made of nickel silver. All wiring which enters the switch is connected with the twelve terminal points 76 through the drilled holes 76a in the manner illustrated in the wiring diagram, Fig. 10, wiring being omitted in the other figures to avoid confusion.

An angular rocker 77, formed of a single piece of metal is secured to the shaft 78 which is pivotally supported in the end bearing pieces 79. The collars 80 prevent endwise movement of shaft 78. The parts 79 are held in place by screws 81. A boss 82 on the lower side of the rocker 77 is drilled to receive one end of the bias spring 83, and the other end of the spring is secured to a lug 84 which is secured to the bottom of the box 71a. The rocker 77 is therefore free to rock back and forth in its bearings, and unless the switch is manually thrown to one or the other operating position, the tension of bias spring 83 will hold the rocker in neutral position with all contacts broken, and the upright rocker arms 85 will assume the position indicated at 85a.

A pair of bars 86 of insulating material are secured to the rocker 77 by screws 90, and these bars extend in cantilever fashion beyond the rocker 77, as is indicated in Fig. 6. At each end of the bars 86 is a hole which loosely fits the pins 87 to permit them to slide freely up and down, the downward motion being limited by the heads 87a. At the lower end of the pins 87 and held in place by the heads 88 are the contact discs 89, which are preferably made of sil-

ver alloy. These are urged downwardly against the heads 88 by the compression springs 91. Since the holes through the contact discs 89 are a loose fit on the pins 87, the discs are afforded freedom of movement with respect to the pins 87. This freedom of movement of the discs 89 enables them to make a perfect three-point contact with the slightly convex surfaces of the points 76 as they are urged downwardly by springs 91, thereby insuring a good electrical connection when the switch is closed. In the drawing, Fig. 7, the switch member on the right hand side is shown in closed position, while the one on the left hand side is open. A wiping contact is effected whenever the switch closes, thereby minimizing the effect of any dust particles or corrosion that may occur upon the contact surfaces. The partition 72a is slotted as indicated to permit free movement of the rocker arms 85 and the stop arms 103.

Mounted upon the partition 72a are a pair of latch members 91 and 91a, which are pivotally mounted on pins 110 and 110a and are held between the bearing pieces 92 and 92a which are secured to the partition by screws 93. The latches are urged upwardly by the springs 94. The stop 95 limits the upward movement of the latches, and downward movement is limited by the stop 96. Stop members 97 and 97a are provided with upwardly turned ears 98, which are pivotally secured to the latches by pins 99. Each of the latches is hollowed out, as indicated by the dotted lines 101, to accommodate springs 102 which urge the stop members downwardly.

Extending between the rocker arms 85 and rigidly attached thereto is the pin 121 which engages the latch member 91 or 91a, as the case may be, to hold the switch in closed and locked position when it is thrown by means of the rod 67. The pin 122 which is fixed to the rocker arms 85 at either end serves as a connection for the control rod 67 which is held in a central position by sleeves 123.

Between the rocker arms 85 are a pair of upwardly extending arms 103, one of which is in line with the latch 91 and the other in line with latch 91a. The object of the arms 103 is to prevent the switch being again closed toward a latch which has been depressed by one of the fingers 71 or 72. The functions of the stops 97 and 97a and the upright arms 103 are best illustrated in Fig. 8 which shows the position of the latch 91 at the point where the travel of the bed has been automatically stopped by the finger 71 depressing the latch 91. The dotted line 85b (Fig. 8) indicates the limit of motion of rocker arm 85 in the event an attempt is made to throw the switch to the position shown in Fig. 7 while the latch 91 is depressed. It will be seen in Figs. 8 and 9 that stop 97 engages arm 103 and prevents it being moved far enough to close the switch while latch 91 is depressed by finger 71. The purpose of the spring 102 is to allow the arm 103 to return freely to vertical position when the latch releases pin 121 from its lowered position and while finger 71 continues to depress latch 91.

In Fig. 10 I have illustrated one successful method of connecting a single-phase, split phase, four-wire reversible A. C. motor. Such motors are commonly built with four connecting wires, two of which connect with the running winding of the motor and two to the starting winding of the motor. Manufacturers usually distinguish the pair of wires which connect with the running winding from the pair which connect with

the starting winding by a difference in size or color of the wires. In the following description it is assumed that the wires connected with the running winding are black, and those that connect with the starting winding red. With such an arrangement the direction of the motor may be changed by reversing the red wires, as will be understood from the following description.

In Fig. 10 the power feed lines, which are assumed to connect with a source of alternating current are indicated by the numerals 110 and 111, respectively. Wires 112 and 113 are assumed to be the black wires leading to the running windings of the motor, and wires 114 and 115 are assumed to be the red wires leading to the starting windings of the motor. The switch indicated by the numeral 116 is for the purpose of shutting off the current leading to the motor for any purposes whatever, and is especially for use in the event it is desired to stop the movement of the bed in any intermediate position. This switch is indicated by the same numeral on the drawing of the bed.

A study of the diagram of Fig. 10 taken in conjunction with Figs. 6 and 7 will make it clear that when the switch is thrown to the position shown in Fig. 7 the red wire 115 connects with the black wire 113 and with the power line 111, while the red wire 114 connects with the black wire 112 and the power line 110; when the switch is thrown toward the left black wire 113 connects with red wire 114 and with power line 111, while black wire 112 connects with red wire 115 and with power line 110. In other words, the reversal of the switch reverses the position of the red wires with respect to their associated black wires and this reverses the motor.

The operation of the switch is as follows: The rocker arms are actuated by the rod 67 to pull the switch into closed position as shown in Fig. 7, the spring action of the latch 91 permits it to be depressed to engage pin 121 as soon as the pin enters the notch of the latch member. This makes contact with the motor as shown in the wiring diagram, the motor turns and the bed slowly raises to its full height. While the bed is raising, the shaft 38 turns slowly in clockwise direction until the finger 71 depresses the latch member 91 to the position shown in Fig. 8, at which point the pin 121 is disengaged by the latch and the bias spring 83 pulls the rocker arms to the vertical position 85a, the electrical circuit is opened and the movement of the bed stops. The latch 91 remains in this depressed position so long as the bed remains at its full height. As shown in Fig. 8, while the latch is thus depressed the stop 91 prevents the upright members 103 from passing. This makes it impossible to throw the switch in the direction of the latch 91, and produce further motion of the shaft in clockwise direction. The only direction in which the switch can now be moved is toward latch 91a. As soon as the switch is thrown for pin 121 to engage the latch 91a contacts are made on the left side of the switch, and immediately the shaft 38 begins to turn in a counter-clockwise direction, raising the finger 71 to permit the spring 94 to return the latch 91 to horizontal position.

It should be noted that after the finger 71 lifts away from the latch 91 and it returns to its upper position, the stop 97 will no longer interfere with the movement of the arm 103; however, the switch remains locked by latch 91a and pin 121 so that it cannot again be moved until finger 72 depresses the latch 91a. Therefore the switch

at all times is automatically locked in such a manner as to prevent it being thrown in the wrong direction. This is important because if the switch could be thrown in the "up" direction after the bed had already been raised to its limit, damage would obviously occur.

If the switch 116 is opened to stop the bed in an intermediate position, such action does not in any way effect the locking features of the switch 61, which resumes its normal functions when switch 116 is again closed.

The toggle construction of the legs affords rigidity to the bed while in its uppermost position and while the cables 22 and 22a are taut. 15 When the bed is in its lowered position the cables are slackened to a slight extent and the weight of the bed rests upon the posts 9 to afford stability while the bed is in lowered position. The working parts of the bed are concealed and protected by the side boards 100, which not only give the bed a pleasing appearance but prevent any possibility of bed clothing from becoming entangled with the moving parts.

In the accompanying drawings, one of the 25 side boards is removed to better illustrate the working parts of the bed.

In the drawings the switch 116 is shown in a location adjacent the switch box 61, but in the practical application of my invention this switch 30 may be located to suit the wishes of the user of the bed, and, if desired, may be located alongside of the knob 69.

I claim:

1. A bed comprising a mattress-supporting member and a base member in parallel relation with each other; a pair of toggles adjacent the head of said bed and another pair of toggles adjacent the foot of said bed; pivotal means to connect one end of each of said toggles with said mattress-supporting member, and pivotal means to connect the opposite ends of each of said toggles with said base member; means to limit end-wise movement of said mattress-supporting member with relation to said base member; a rotatable shaft intermediate of the head and foot of said bed; motor means to rotate said shaft; cables secured to said toggles adjacent the junction points thereof; cams fixedly secured to said shaft; means to secure said cables to said cams to exert a pulling force upon said cables to straighten the toggles and elevate the mattress-supporting member when the cams are rotated in a certain direction, and to pay out said cables and reverse the action of said toggles to lower the mattress-supporting structure when the cams are rotated in the opposite direction; means to reverse the direction of rotation of said shaft and cams.

2. A bed comprising a mattress-supporting structure; a base member adapted to sustain said mattress-supporting structure in parallel relation with said base; toggle members adjacent each of the four corners of said bed and adapted to serve as legs therefor; a cam shaft; a plurality of cams fixed to said shaft; motor means to drive said shaft; cables secured to said toggles adjacent the junction points thereof; means to secure said cables to said cams to exert a pulling force upon said cables to straighten the toggles and elevate the mattress-supporting structure when the cams are rotated in a certain direction and to pay out said cables and reverse the action of said toggles to lower the mattress-supporting structure when the cams are rotated in

the opposite direction; each of said cams having its working surface graduated in distance from the axis thereof to provide maximum leverage when the mattress-supporting structure is at its lowest level, and to gradually diminish in leverage as the mattress-supporting structure is elevated; means to reverse the direction of rotation of said shaft and cams.

3. The structure as set forth in claim 2, including a limit switch for controlling said motor means actuated by movable means driven by said power means in timed relation with the movement of said cams.

4. A bed comprising mattress-supporting means and a base member in parallel relation with each other; a pair of toggles adjacent the head of said bed and another pair of toggles adjacent the foot of said bed; pivotal means to connect one end of each of said toggles with said base, and pivotal means to connect the opposite ends of said toggles with said mattress-supporting means; means to limit endwise movement of said mattress-supporting means with relation to said base member; a rotatable shaft intermediate of the head and foot of said bed; power means to rotate said shaft; cable means to connect the junctions of said toggles with rotatable elements fixedly secured to said shaft; switch means to control said power means; manual means to close said switch and automatic means for opening said switch; means connecting said automatic switch-opening means in timed relation with the movement of said power means and said mattress-supporting means to open said switch automatically when said mattress-supporting means reaches a pre-determined position; locking means to lock manual switch-closing means and prevent movement thereof while said mattress-supporting means is in an intermediate position.

5. A bed comprising a mattress-supporting structure; a base member adapted to carry said mattress-supporting structure; a pair of toggles adjacent each end of said bed, each of said toggles having a hinged joint near one extremity thereof connected to the mattress-supporting structure and a hinged joint adjacent the opposite end thereof connected to the base member; an electric motor carried by said mattress-supporting structure to be raised and lowered therewith; a transverse shaft mounted in fixed relation to said mattress-supporting structure and geared to said motor; cams fixedly mounted upon said shaft; a plurality of cables, each having one terminal fixed to one of said cams and its opposite terminal fixed to one of said toggles; each of said cams having its working surface graduated in distance from the axis thereof to impart a relatively slow rate of motion to its connected cable when the mattress-supporting structure is in its lowermost position, and a gradually increasing rate as the mattress-supporting structure rises; a switch to control said motor; a switch-actuating lever mounted to move in timed relation with said shaft to stop the action of said motor as the mattress-supporting structure approaches its limit of travel.

6. A bed comprising a base member and a mattress-supporting structure; a plurality of toggles to connect said base member and mattress-supporting structure; a motor to straighten the toggles to elevate the mattress-supporting structure; means to connect said motor with said toggles including a cam to vary the leverage of power application and provide maximum leverage to said toggles when the mattress-supporting struc-

ture is in its lowermost position, and a diminishing leverage as the mattress-supporting structure rises; switch-actuating means mounted upon a moving part of said bed to travel in timed relation with said cam to stop said motor when said mattress-supporting structure reaches a predetermined position.

7. A bed comprising a base member and a mattress-supporting structure; toggles adjacent the ends of said bed to connect said base member and mattress-supporting structure; motor means to actuate said toggles to raise and lower the mattress-supporting structure; connecting means to transmit the power of said motor means to said toggles, including a variable leverage mechanism which applies its maximum leverage to said toggles when the angle of leverage of the toggles is at its minimum, and a gradually decreasing leverage to said toggles as the angle of leverage of the toggles increases; switch means to control the motor, including a limit switch to stop said motor when said mattress-supporting structure reaches a predetermined position.

8. A bed comprising a base member and a mattress-supporting structure; toggles adjacent the ends of said bed to connect said base member and mattress-supporting structure; a transverse shaft disposed upon the under side of said mattress-supporting structure; a motor to drive said shaft; cable-winding means upon said shaft; a cable to connect each toggle with said cable-winding means to straighten said toggles and thereby elevate said mattress-supporting structure; a manually controlled switch to start said motor; means to lock said switch in operative position during the upward or downward travel of said mattress-supporting structure; switch-actuating means mounted to move in timed relation with said mattress-supporting structure to stop said motor when the mattress-supporting structure reaches a predetermined limit of travel.

9. A bed comprising a mattress-supporting structure; a base member adapted to carry said mattress-supporting structure; a pair of toggles adjacent each end of said bed, a pivotal joint near one extremity of each toggle to connect the toggle to the mattress-supporting structure, and a pivotal joint adjacent the opposite end to connect the toggle to the base member; an electric motor mounted in fixed relation to said mattress-supporting structure to be raised and lowered therewith; a transverse shaft mounted in fixed relation to said mattress-supporting structure and geared to said motor; cable-winding means mounted upon said shaft; a cable having one end fixed to each of said toggles, and the opposite end fixed to said cable-winding means to straighten said toggles when said cable-winding means is rotated in a certain direction, and to pay out said cables and reverse the action of said toggles when said cable-winding means is rotated in the opposite direction; resilient means to force the bending of said toggles during the initial stage of lowering said mattress-supporting structure; a switch to control said motor; an adjustable switch actuator mounted to move in timed relation with said cable-winding means to actuate said switch and stop the action of said motor when the mattress-supporting structure reaches a predetermined level.

10. A bed comprising a mattress-supporting member and a base member in parallel relation with each other; a pair of toggles adjacent the head of said bed and another pair of toggles adjacent the foot of said bed; pivotal means to con-

11

nect one end of each of said toggles with said mattress-supporting member, and pivotal means to connect the opposite ends of each of said toggles with said base member; means to limit endwise movement of said mattress-supporting member with relation to said base member; a rotatable shaft intermediate of the head and foot of said bed; motor means to rotate said shaft; cables secured to said toggles adjacent the junction points thereof; cable winding means fixedly secured to said shaft; means to secure said cables to said cable winding means to exert a pulling force upon said cables to straighten the toggles and elevate the mattress-supporting member when the cable winding means are rotated in a certain direction, and to pay out said cables and reverse the action of said toggles to lower the mattress-supporting structure when the cable winding means are rotated in the opposite direction; means to reverse the direction of rotation of said shaft and cable winding means.

11. A bed comprising a base member and a mattress-supporting structure; toggles adjacent the ends of said bed to connect said base member and mattress-supporting structure; a transverse shaft disposed upon the under side of said

12

mattress-supporting structure; a motor to drive said shaft; cable-winding means upon said shaft; a cable to connect each toggle with said cable-winding means to straighten said toggles and thereby elevate said mattress-supporting structure; a manually controlled switch to start said motor; switch-actuating means mounted to move in timed relation with said mattress-supporting structure to stop said motor when the mattress-supporting structure reaches a predetermined limit of travel.
